UNITED STATES PATENT OFFICE

170,159

PORTABLE LAVATORY

Isadore Levin, Washington, D. C.

Application March 12, 1953, Serial No. 24,000

Term of patent 14 years

(Cl. D4—2)

To all whom it may concern:

Be it known that I, Isadore Levin, a citizen of the United States, residing at 5814 3rd Street N. W., city of Washington, District of Columbia, have invented a new, original, and ornamental Design for a Portable Lavatory, of which the following is a specification, reference being had to the accompanying drawing, forming a part thereof, in which:

Figure 1 is a perspective view of a portable lavatory showing my new design; Figure 2 is a perspective view similar to Figure 1 but showing the other side thereof; Figure 3 is a top plan view;

Figure 4 is a side view in elevation; Figure 5 is a front view in elevation; and Figure 6 is a rear view in elevation.

I claim:

The ornamental design for a portable lavatory, as shown.

ISADORE LEVIN.
